UNITED STATES PATENT OFFICE

162,151

REFRIGERATOR BOX OR SIMILAR ARTICLE

Robert K. Gibbs, Evansville, Ind., assignor to Tri-State Plastic Molding Co., Henderson, Ky., a limited partnership

Application June 2, 1948, Serial No. 146,723

Term of patent 14 years

(Cl. D44—1)

To all whom it may concern:

Be it known that I, Robert K. Gibbs, a citizen of the United States and a resident of Evansville, Indiana, have invented a new, original, and ornamental Design for a Refrigerator Box or Similar Article, of which the following is a specification, reference being had to the accompanying drawing, forming part hereof:

In which:

Fig. 1 is a top plan view of a refrigerator box or similar article showing my new design;

Fig. 2 is a side elevational view with the lid in raised position;

Fig. 3 is a bottom plan view;

Fig. 4 is an end elevational view; and

Fig. 5 is another side elevational view thereof with the lid in nesting relationship.

I claim:

The ornamental design for a refrigerator box or similar article as shown and described.

ROBERT K. GIBBS.
